FRANZ SCHWEIZER, OF HOF, GERMANY, ASSIGNOR TO KARL HINTSCHES, OF OBER-KOTZAU, GERMANY

DEVICE FOR PREVENTING CARBURETOR FIRES

Application filed August 6, 1930, Serial No. 473,498, and in Germany June 26, 1930.

- Attempts have been made repeatedly to reduce to a minimum the danger resulting from the frequently occurring carburetor- or motor-fires on motor cars and the like.
- 5 The cause for carburetor fires is any irregularity of the motor whereby the ignited or incandescent gas mixture flows from the cylinders through the feed pipes into the carburetor and ignites the explosive mixture in the same, whereby further ignition of the fuel in the fuel feed pipes and in the tank is caused, so that the car is destroyed and serious or deadly injuries of the passengers and driver happen.
- 10 Even when the motor is attended with care, it happens, especially in the course of a long service, either that foreign bodies get into the valve seats so that the valve shaft jams in its guides or the valve spring breaks, or incandescent oil-carbon collects in the cylinder.

15 All these irregularities or defects in the motor cause overheating of the same and eventually, owing to the back firing of the 20 gases from explosion through the badly fitting suction valves, fires in the carburetor or even in the tank.

An arrangement is therefore wanted which, with absolute security, interrupts the 25 fuel admission instantaneously, as soon as the motor is heated above a certain degree, so that fires in the carburetor or in the motor can no longer occur.

This invention relates to an apparatus 30 which is arranged in proximity to and above the carburetor and inserted in the fuel supply pipe. This apparatus consists of a valve arrangement, constructed so that the spring-controlled valve body shuts off the fuel supply pipe only when the motor blocks or the carburetor has been heated to a temperature, which is excessive but still below the dangerous temperature.

According to the invention the shutting off 35 valve is held open, when the spring is under tension, by an element, which consists of easily combustible material, possessing however below the ignition point a sufficient resistance to maintain the valve in the open position in opposition to the action of the spring.

As the new apparatus is arranged directly above the carburetor, the element maintaining the valve in the open position directly facing the carburetor, the absolutely secure function of the apparatus is assured. The 55 easy combustible element will ignite readily at overheating of the carburetor to a degree of heat, which is not yet dangerous, i. e. before igniting of the carburetor can occur, and the valve liberated by the ignited element 60 will shut off the fuel admission to the carburetor.

An embodiment of the invention is illustrated by way of example in the accompanying drawing in which:

Fig. 1 shows in front elevation the apparatus to be inserted into the fuel supply pipe of the carburetor.

Fig. 2 shows a central vertical section of the apparatus, the valve being in the open 70 position.

Fig. 3 is a similar view as Fig. 2, the valve being closed.

The apparatus, according to the invention, 75 consists of a short tube *a* with tubular sockets *b* and *c*. The short tube *a* has an enlarged lower end *d*. In the tube *a* a bush *e* is inserted, the lower end of which is flush with the inner surface of the enlarged portion *d*, and a spindle *f* of the valve body *g* is guided 80 in this bush, into which it fits closely. A pressure spiral spring *h* is wound around the spindle, bearing at the upper end against the valve body *g* and at the lower end against the bush *e*. The lower portion *i* of the spindle *f*, projecting into the enlarged part *d* of tube *a*, is screw threaded and extends through a central hole of a disc *k* the rim of which engages in a groove *m* in the lower end of the enlarged part *d* of the tube *a*. A nut *n*, 90 screwed on the screw threaded part *i* of the spindle *f* below the disc *k*, serves for lowering the valve body *g* in opposition to the action of spring *h*. The disc *k* is made of an easily ignitable material, such as celluloid, 95 possessing however sufficient resistance to maintain the valve body *g* in the open position in opposition to the action of spring *h*.

On the lower externally threaded portion 100 of the enlarged part *d* of tube *a* a screw cap

o is screwed, which has a large aperture *p* in its bottom plate through which a semi-spherical segment or cap *q* projects, the edge of which is clamped between the screw cap *o* and the end of part *d*. This semi-spherical segment *q* is preferably made of thin uncom-bustible material possessing a good heat conducting property. This semi-spherical segment might however also be made of easily combustible material, such as celluloid.

10 The fuel supply pipe *r* from the tank is connected with the tubular socket *b* by a connecting nipple *s*. To the tubular socket *c* a connecting tube *t* is connected by means of a nipple *u*, the other end of tube *t* being connected to the carburetor *v*.

The operation is as follows:

20 If, for any reason whatsoever, excessive heating of the motor should occur, which might result in a carburetor- or engine-fire, the disc *k* will ignite, and also the spherical segment *q*, if the same is made of celluloid. As soon as the disk *k* has been ignited, the valve body *g* is released and will be lifted by the action of the spiral spring *h* into the position shown in Fig. 3 and interrupt the communication between the fuel supply pipe *r* and the connecting tube *t* of the carburetor *v*, i. e. between the benzine tank and this carburetor, so that no carburetor fire can occur or, if a carburetor fire has started, this fire is instantaneously extinguished, as no fuel is fed to the same.

30 The apparatus can be easily made ready for renewed use by removing the screw cap *o* and the nut *n*, whereupon a fresh disc *k* is pushed on the spindle *i* and secured in position by means of the nut *n*, which is tightened until the valve body *g* has been sufficiently lowered against the opposition of spring *h* to reestablish the communication between the fuel tank and the carburetor. The semi-spherical segment *q* is inserted and the screw cap *o* screwed on.

40 I claim:—

1. An apparatus for preventing carburetor fires, comprising in combination with the fuel supply pipe from the fuel tank and the pipe connected to the carburetor, a short tube connecting the adjacent ends of said pipes and having an enlarged lower end, said tube having an annular groove near the lower end of its inner surface, a guide bush in said tube, a valve spindle closely fitting and guided in said bush, a valve carried by said spindle and tending to move to a position to shut off the flow of fuel through said pipes, a screw threaded lower end of said valve spindle, a celluloid disc having a central hole pushed over the lower end of said valve spindle and engaging in said groove in the inner surface of said enlarged portion, and a nut screwed on the end of said screw threaded spindle below said celluloid disc.

50 2. An apparatus for preventing carburetor

fires, comprising in combination with the fuel supply pipe from the fuel tank and the pipe connected to the carburetor, a short tube connecting the adjacent ends of said pipes and having an enlarged lower end, said tube having an annular groove near the lower end of its inner surface, a guide bush in said tube, a valve spindle closely fitting and guided in said bush, a valve carried by said spindle and tending to move to a position to shut off the flow of fuel through said pipes, a screw threaded lower end of said valve spindle, a celluloid disc having a central hole pushed over the lower end of said valve spindle and engaging in said groove in the inner surface of said enlarged portion, a nut screwed on the end of said screw threaded spindle below said celluloid disc, a screw cap screwed on the lower end of said enlarged tube part having a large central aperture in its bottom plate, and a semispherical cap held at its edge between said screw cap and the lower end of said enlarged tube part and projecting through said central aperture of said screw cap.

60 In testimony whereof I affix my signature.
FRANZ SCHWEIZER.
